UNITED STATES PATENT OFFICE

FRED KNORR, OF DENVER, COLORADO

IRONING BOARD

Application filed September 15, 1930. Serial No. 481,928.

This invention relates to improvements in ironing boards of the type that can be attached to the edge of a table or to the edge of a sink or other suitable projecting ledge.

It is customary to make ironing boards that are formed from a single board having a slot or opening at its widest end and having the end of a supporting bar extending through this opening and hinged to the board so as to form with the board a pair of tongs that engage the edge of the table.

Ironing boards of the type just described are so constructed that the supporting bar is permanently attached to the board with the result that the board cannot be used as an ordinary ironing board as the supporting bar prevents it from being laid on a flat surface or on two spaced supports. Ironing boards of the type to which this invention relates are also, as a rule, provided with lugs or ears on opposite sides of the slot or opening in the end of the board and the hinge pin extends through these ears and through the supporting bar, and therefore, even if the supporting bar is removed, the ironing board will not be adapted to be used in the ordinary manner because of the presence of the ears or lugs.

It is the object of this invention to produce an ironing board of the general type to which reference has just been made and which shall be so constructed that the supporting bar can be quickly separated from the board thereby leaving the latter like an ordinary ironing board with both sides flat and it can therefore be used in the ordinary way by laying it on a table or supporting it on the back of spaced chairs or on any other spaced support.

The fact that the board and the support can be readily separated from each other is a great convenience also for the reason that the support and the board can then be stored separately and will occupy much smaller space and be much handier to handle than if they were permanently connected.

The above and other objects that may become apparent as this description proceeds are attained by means of a construction and

an arrangement of parts that will now be described in detail, reference for this purpose being had to the accompanying drawings in which the preferred embodiment of the invention has been illustrated, and in which:

Fig. 1 is a side elevation of the improved ironing board showing the same attached to the edge of a table, a portion of the board being broken away to better disclose the construction;

Fig. 2 is a section through one end of the ironing board showing the manner of attaching the supporting bar thereto, a portion of the bar being shown broken away so as to better disclose the construction; and

Fig. 3 is a view of the underside of the ironing board showing the relative position of the slot and the pivot pin.

In the drawings numeral 1 designates the surface of the floor and 2 the top of a table such as a kitchen table and this is supported by legs 3 in the ordinary manner.

Numerical 4 indicates the ironing board which is of the usual length and width and which has a pointed outer end 5. The other end of the ironing board which is termed the inner end has been designated by reference numeral 6 and is provided with a slot or opening 7 that extends inwardly a short distance as shown in Figs. 2 and 3. A pivot pin 8 is attached to the ironing board near the inner end of the slot. This pivot pin can be made in different ways but has been shown as formed from a metal bar having flattened end portions 9 and a cylindrical central portion. The board is preferably provided with a transverse depression 10 of sufficient depth to place all parts of the pivot pin beneath the lower surface of the board and the pivot pin is held in place by means of screws 11. Since the pivot pin is recessed into the board, both surfaces of the board are plane and it can therefore be used as an ordinary ironing board and can be laid on a flat table or any other support.

The pivot pin is so constructed that it will extend substantially the entire distance across the board and therefore prevents the latter from becoming split if subjected to rough handling.

The supporting bar has been designated by reference numeral 12 and has a width substantially equal to the width of slot 7. Secured to one side of the bar near its upper 5 end is a metal plate 13 that is provided on its outer side with a plurality of transverse, cylindrical depressions 14 that are adapted to receive the pivot pin in the manner shown in Fig. 2. This plate can be dispensed with 10 and notches provided in the surface of bar 12 but the plate is believed to be preferable for the reason that if the notches are cut in the wooden bar, the portions between the notches are liable to break away and 15 make it difficult to secure proper adjustment. The plate 13 is held in place by means of rivets 15 which also serve to prevent the bar from splitting. The upper end of the bar is provided with a rectangular notch 16 on 20 its lower surface and this is adapted to receive the edge of the table top 2 for the purpose of clamping the ironing board in place thereon. The notches in plate 13 are for the purpose of permitting adjustments to be 25 made so that the board will fit table tops of different thickness, as it is only necessary to move the pivot pin from one notch 14 to another in order to secure the proper adjustments. If the bar 12 were attached to 30 the board by means of a pivot pin going through the bar itself, as is customary, greater difficulty would be experienced in making proper adjustments and this is therefore an added advantage that is derived from the 35 present construction. Since the pivot pin 8 is located quite near the inner end of the board, it is necessary to provide a brace to support the board because in the absence of such a brace, the board will yield so as to 40 make it an unsatisfactory surface for ironing and for this purpose I have provided a brace 17. This brace is provided at one end with a longitudinal slot 18 through which the bolt 19 extends. This bolt is 45 provided with a wing nut 20 and is used for clamping the brace in adjusted position. The under surface of the board 4 has a notch 21 for the reception of the upper end of brace 17. When the parts are adjusted as 50 shown in Fig. 1 the board is very rigid and forms a satisfactory support for ironing clothes and after the board has been used, it can be easily separated from the table and the two parts of the board separated from 55 each other so as to facilitate storage.

From the above description it will be apparent that I have produced an ironing board of such construction that the board and its support are unattached from each 60 other and can be quickly separated and stored in separate places and as quickly reassembled to form an operative device which can be attached to the edge of a table or other stationary flange. I want to call particular 65 attention to the construction that makes it

possible to connect the support and board so as to form an operative assembly without permanently interconnecting them and in such a way that both sides of the board are unobstructed when the supporting bar is removed.

Having described the invention what I claim as new is:

An ironing board having both surfaces formed from unobstructed planes, one end of the board having a notch or opening extending inwardly therefrom, a metal bar secured to the under side of the board and extending transversely of the opening with the bar rounded in the portion extending across the opening, the metal bar lying wholly within the space bounded by the two opposite sides of the board, and a supporting bar having one end extending through the opening, the upper edge of the bar having a plurality of transverse notches adapted to receive the rounded portion of the metal bar and the underside having a rectangular notch at the upper end of the bar.

In testimony whereof I affix my signature. 90
FRED KNORR.
